RADIATOR HEAT DRIVEN MOVING TOY

Filed Oct. 30, 1929

INVENTOR.
Aurelio Cesario
BY *John Holachuk*
ATTORNEY

UNITED STATES PATENT OFFICE

AURELIO CESARIO, OF NEW YORK, N. Y.

RADIATOR-HEAT-DRIVEN MOVING TOY

Application filed October 30, 1929. Serial No. 403,382.

This invention relates to new and useful improvements in a radiator heat driven moving toy.

The invention has for an object the provision of a device of the class mentioned which is of simple durable construction, dependable in use and efficient in action, and which can be manufactured and sold at a reasonable cost.

10 The invention proposes a novelty figure mounted on a radiating heat sensitive rotative member, and means for rotatively supporting said heat sensitive rotative member upon a radiator in the path of motion of its 15 heat.

For further comprehension of the invention, and of the objects and advantages thereof, reference will be had to the following description and accompanying drawings, and to 20 the appended claims in which the various novel features of the invention are more particularly set forth.

In the accompanying drawing forming a material part of this disclosure:—

25 Fig. 1 is an elevational view of a device constructed according to this invention.

Fig. 2 is an edge elevational view of the device shown not applied upon the radiator.

30 Fig. 3 is a fragmentary side elevational view looking in the direction of the line 3—3 of Fig. 2, but shown with the clothing removed.

Fig. 4 is a horizontal sectional view taken on the line 4—4 of Fig. 3.

35 Fig. 5 is a fragmentary elevational view of a device constructed according to modified form.

Fig. 6 is a fragmentary vertical sectional view taken on the line 6—6 of Fig. 5.

40 Fig. 7 is an elevational view of the device constructed according to another embodiment of the invention.

The radiator heat radiating moving toy consists of a novelty figure 10 mounted upon 45 a radiating heat sensitive rotative member 11, and a means for rotatively supporting said heat sensitive rotative member upon a radiator 12 and in the path of motion of its heat.

In Figs. 1 to 4, the novelty figure is shown 50 consisting of a flat placard 13 shaped and

ornamented to simulate a dancing girl, cloth material 14 wound about the placard so as to simulate a veil or dress upon the dancing girl and smartly combined with the radiating heat sensitive rotative member to cause the latter 55 element to simulate the skirt portion of the girl's dress in elevated condition as though the dancer was spinning. The said heat radiating sensitive rotative member consists of a flat horizontal member 15 attached on the 60 placard and formed with radial cuts 16 forming a plurality of wings 17 and these wings are twisted to cause rotation upon the passage of a current of air.

The said means for rotatively supporting 65 said heat sensitive rotative member consists of a vertical tube 18 with a closed top 19 and secured upon the placard 13 beneath the dress material 14. The attachment is accomplished by strips 20 attached on the tube and secured 70 upon the placard. A vertical support wire 21 has its top end engaged in the tube 18 accomplishing the rotative mounting and a means is provided at the bottom of the vertical wire for accomplishing attachment upon 75 the radiator. Said means preferably is arranged resiliently for maintaining its attached position so as to be conveniently detachable.

The said means at the bottom of the vertical wire 21 for accomplishing the attachment upon the radiator consists of parallel spaced horizontal turns of wire 22, connected as hereinafter described. These coils are compressible and may be engaged between the 80 leaves of the radiator. In Fig. 1 these coils are shown compressed and inserted between the leaves and in this condition firmly hold the vertical wire 21 so that the novelty figure 85 may rotate thereon.

In the modified form illustrated in Figs. 5 and 6, the novelty figure consists of a conventional pin-wheel 23 arranged to simulate a flower and nude baby dolls 24 attached upon the top of the flower. The said pin-wheel 95 constitutes the radiating heat sensitive rotative member. The means for rotatively supporting said heat sensitive rotative member consists of a vertical tube 25 extending thru the center of the pin-wheel and flanges 26 100

attached upon the tube and coacting with the pin-wheel for accomplishing the attachment. The top end 27 of the tube 25 is closed and the support wire 21 engages in this tube and accomplishes the rotative supporting.

The connection before referred to between the vertical wire 21 and the parallel spaced horizontal turns of wire 22 consists of a plate 28 attached upon the lower end of the vertical support wire 21, a pair of parallel spaced horizontal wire coil sections 29 pivotally attached upon the plate, and a means for holding the coil sections in various angular adjusted positions. The latter means consists of wing set screws 30 engaged thru the pivot points of the coil sections. This arrangement permits the coil sections to assume various spread positions and adapt the tube for firm attachment upon radiators in which the leaves differ slightly from each other.

In Fig. 7, a device has been shown constructed according to modified form. It consists of a plurality of novelty figures 32 mounted upon plurality of radiating heat sensitive rotative members 33, and a single means for rotatively supporting said heat sensitive rotative members upon a radiator and in the path of motion of its heat. Said support consists of a plurality of vertical support wires 21' attached upon a common connector wire 34. A pair of support means 35 is connected with the connector wire 34 and is adapted for attachment upon a radiator in manners similar to those described.

In operation, the various devices are engaged upon a radiator as described. The heat from the radiator causes the air in its vicinity to rise. This current of air engages against the radiating heat sensitive rotative members and accomplishes rotation.

It is to be understood that the flat placard 13 may be of any desired material and may be substituted by other than flat shape bodies, such as porcelain, light metal etc.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In a radiator heat driven moving toy, a vertical wire for rotatively supporting a heat sensitive rotative member, a plate attached upon the lower end of said wire, a pair of parallel spaced horizontal wire coil sections pivotally attached upon said plate, and means for holding the coil sections in various adjusted positions so as to adapt the wire for firm attachment upon radiators in which the width between the leaves differ.

2. In a radiator heat driven moving toy, a vertical wire for rotatively supporting a heat sensitive rotative member, a plate attached upon the lower end of said wire, a pair of parallel spaced horizontal wire coil sections pivotally attached upon said plate, and means for holding the coil sections in various adjusted positions so as to adapt the wire for firm attachment upon radiators in which the width between the leaves differ, said means comprising wing set screws attached between the plate and the pivot points of said coil sections. 70

3. In a radiator heat driven moving toy, a vertical wire for rotatively supporting a heat sensitive rotative member, a plate attached upon the lower end of said wire, a plurality of parallel spaced horizontal wire coil sections pivotally attached upon said plate, and wing set screws attached between the plate and the pivot points of said coil sections for holding the coil sections in various adjusted positions so as to adapt the wire for firm attachment upon radiators in which the width between the leaves differ. 80

4. In a radiator heat driven moving toy, a vertical wire for rotatively supporting a heat sensitive rotative member, a plurality of parallel spaced horizontal wire coil sections for attachment upon a radiator, and a means for pivotally connecting the coil sections with the lower end of the vertical wire for allowing attachment of the coils upon radiators in which the width between the leaves differ. 95

In testimony whereof I have affixed my signature.

AURELIO CESARIO.
